UNITED STATES PATENT OFFICE.

GEORGE A. WILSON, JR., OF BOSTON, MASSACHUSETTS.

AUTOMATIC TRAIN-ARRESTOR AND RAILROAD SIGNAL SYSTEM.

1,119,740.

Specification of Letters Patent.

Patented Dec. 1, 1914.

Application filed July 14, 1913. Serial No. 778,880.

To all whom it may concern:

Be it known that I, GEORGE A. WILSON, Jr., citizen of the United States, residing at Boston, county of Suffolk, State of Massachusetts, have invented a certain new and useful Improvement in Automatic Train-Arresters and Railroad Signal Systems, of which the following is a specification, reference being had therein to the accompanying drawings.

My invention has for its object mechanism by which a train, whether operated by steam or electricity, may be brought to a stop or its speed reduced to a predetermined point if it passes a block signal which is set at danger or in the cautionary position.

The apparatus embodying my invention consists in a contact device operated by the semaphore or signal arm of a block signal, an auxiliary or so-called third rail adjacent the track and located near the block signal by which the device is operated, said third rail being provided preferably with a plurality of electrically independent contact surfaces which are connected with the contact device operated by the semaphore or signal arm, a suitable third rail shoe, throttle or rheostat and air brake operating devices to control the motor power and the brakes, and suitable connections to the third rail shoe, together with certain other devices which will be hereinafter more fully described.

The source of power to operate the apparatus is carried by the train, and the portion of the circuit not on the train is dead except when the shoe is in contact with the third rail so that the system is free from all danger of becoming grounded. Mechanism is also provided by which the speed of the train may be reduced below a predetermined point if the train runs by the signal when it is in the cautionary position. If the train passes a block signal which is in the safety position it will not be stopped nor will its speed be affected. Devices are provided so that under proper conditions the train may be moved after having been stopped by the automatic stop. In case of failure of the source of energy or of grounding of any of the circuits, the stop signal is displayed and the train brakes are applied. The contact between the third rail and the vehicle is made by means of a shoe projecting from the truck or the lower part of the car so that the clearance is not interfered with,

nor is the operation of the device affected by speed, shocks, weather, wear of the tracks or vehicle, or oscillation of the vehicle. I also combine with my apparatus simple mechanism by means of which the condition of the signals in the block will be indicated both in the cab of the locomotive and at one or more points in the train, so that the conductor as well as the engineer may be informed as to the condition of the signals even though the block signal cannot be seen. One of the signals in the cab will always be displayed. Telephonic communication between the conductor and the engineer may also be conveniently provided.

The cab signal system is so constructed that that part of the circuit which operates the cab signals, brakes, etc., is not momentary in its operation, lasting only as long as the shoe is in contact with the contact rail, but on the contrary the current therein flows continuously until the circuit is broken by a change of signals, or by positive action by the person in control.

Provision is made so that when the brakes have been set by the operation of the device they cannot be released until after the train has been brought to a stop, and then only by the conductor.

The apparatus is non-inductive, and therefore is not likely to be interfered with in its operation by neighboring electric circuits, such for instance as third rail or power or lighting circuits. The apparatus embodying my invention is also provided with mechanism for recording the number of times the automatic stopping device is operated or the brakes automatically applied, and a bell may be caused to ring in the cab when the brakes are applied. In case the current delivered by the battery by which the apparatus is operated falls below a predetermined point, an alarm bell will be rung or the train will be stopped as may be desired.

The invention will be fully understood from the following description taken in connection with the accompanying drawings, and the novel features thereof will be pointed out and clearly defined in the claims at the close of the specification.

Referring to the drawings, Figure 1 is a diagrammatic view of an apparatus embodying my invention and adapted for use on electrically operated trains. Fig. 2 is a plan view of the electrically operated air-

valve 50. Fig. 3 is a side elevation of the said air valve 50, taken from the right side as seen in Fig. 2. Fig. 4 is a diagrammatic view of an apparatus embodying my invention as applied to a steam operated train. Fig. 5 is a detail of the revolving switch operating the speed reducing throttle valve seen at 104 in Fig. 4.

In the drawings and referring particularly to Fig. 1, at A and B are shown the rails, said rails resting on the sleeper C, and being grounded at M in the usual manner. At D is indicated the post of a block signal, and at E is shown the signal arm or semaphore. At 1' is indicated an auxiliary or third rail provided in the form shown in the drawings with a plurality of contact surfaces 2, 3, and 4, which are preferably parallel and formed lengthwise of the rail as shown in Fig. 1, being separated from each other electrically by the insulation 5 and 6. The number of contact surfaces will be varied according to the requirements of the system. If, for instance, it is desired to provide simply an automatic stop without mechanism for reducing the train speed only a single contact surface will be sufficient. The third rail 1 is insulated from the ground by the insulation 7 on which it rests.

The semaphore arm E swings on an axis 8. This axis 8 is grounded as shown at 20 and is provided at one end with a contact arm 9 which swings with the semaphore arm E. On a stationary quadrant 10 are located three contact points 11, 12 and 13 in the path of the moving contact carried on the end of the arm 9. These three contact points 11, 12 and 13 are so located that when the red or danger signal is displayed, as shown in Fig. 1 the arm 9 is in contact with the contact point 13, while when the yellow or cautionary signal is displayed contact is made with the contact point 12, and when the green or safety signal is displayed contact is made with the contact point 11. The contact point 11 is connected with the portion 3 of the third rail by wire 14 and said connection forms a part of the green or safety circuit, said circuit being shown by a fine continuous line in Fig. 1. The contact point 12 is connected with the portion 4 of the third rail by wire 15. This circuit is indicated by dotted lines in the diagram and is referred to as the yellow or cautionary circuit. The contact 13 is connected with the central portion 2 of the third rail by wire 16. This circuit is known as the red or danger circuit, being shown by a heavy continuous line in Fig. 1. The safety and cautionary circuits in portions of the system coincide with portions of the danger circuit employing the same wires. Where this is the case, the wiring has been indicated as a part of the red circuit.

Secured to an arm F on the car, is a shoe

having three contacts corresponding respectively to the three contact surfaces of the third rail. The two side contacts 17 and 18 contact with the two side portions 3 and 4 respectively of the rail and the top contact member 19 runs on the top of the central portion 2 of the rail. I prefer to arrange the contacts as described, because this construction insures the best contact for the red or danger circuit.

At 31 is shown the battery by which current is supplied to operate the system. The three circuits are connected to a main switch 21 by which all three circuits may be broken simultaneously when it is desired to disconnect the third rail shoe from the rest of the system, as is sometimes temporarily necessary. An instance of this necessity is when it is desired to back out of a block which has once been entered, and upon entering which the train has been automatically stopped.

As my apparatus is shown in Fig. 1 as adapted for the control of an electrically operated train, I have shown at 22 in Fig. 1 in very heavy continuous lines a power circuit. At 23 is shown the source of energy by means of which the train is operated, as for instance a generator or storage battery. At 24 is shown the controller or rheostat, by means of which the flow of current from the source of energy 23 to the motor 25 of the train is controlled. In this circuit is placed a circuit breaker 26 operated by the red or danger circuit, also a resistance 27 which is introduced into the power circuit 22 by means of an automatic switch 28 through wires 29 and 30 whenever the train runs by a yellow or cautionary signal as will hereinafter be more fully explained. Under normal conditions that is except when the danger circuit is operating, this circuit breaker 26 is closed so that the power circuit is completed. In Fig. 1 the circuit breaker 26 is shown as open, the power circuit being broken since the red or danger circuit is then operating.

The red or danger circuit and its operation will first be described. When the semaphore arm E together with the contact arm 9 is set at danger, as shown in Fig. 1, that is with the contact arm 9 in contact with the contact point 13, the red or danger circuit (indicated by a heavy continuous line) will be grounded at 20. Thereafter, when the train enters the block corresponding with this semaphore, and the contact member 19 of the third rail shoe contacts with part 2 of the third rail the entire red or danger circuit is completed, a portion of this circuit being contained in the signal post, third rail and their connections and the other portion of the circuit being carried by the train. Starting from the battery 31 on the train, the current will then pass from the battery 31 through the wires 32 and 33

to the circuit closing relay 34, then through the switch 21 to the contact member 19. Thence it will pass to the ground 20 through the various connections previously described. From the ground 20 it will pass to the ground 35. Then the current will flow through wire 36 to wire 37 along wire 37 to wire 38. The current then flows through the open circuit relay 39 and wire 40 to the 10 battery 31, thus completing the red or danger circuit. The passage of the current as described from the battery 31 through the circuit closing relay 34 operates the said relay and closes a circuit, which is a shunt 15 circuit of the red or danger circuit. The said circuit closing relay 34 is arranged to remain closed after having once been operated until the lever 41 has been depressed. In practice, it is desirable to have this relay 20 34 located in a locked box, the key to which is in the possession of the conductor or other suitable employee. When the circuit closing relay 34 has closed the shunt circuit, current flows from the battery 31 through wires 25 32 and 321 then through the armature of the circuit closing relay 34 to the wire 42. The current then branches off, a portion of it going through wire 43 and the other part going through wire 44. That part of the 30 current passing through wire 43 operates the recording device 45 and the alarm bell 46. It then passes through wire 47 to the circuit breaker 26. By attracting the armature of the circuit breaker 26 the power circuit 35 is broken and the current to the motor 25 of the train is shut off. Thereafter the current passes through wire 48 to wire 37 and thence returns to the battery 31, through wire 38, relay 39, and wire 40. Another 40 part of the current in the wire 43 passes through the wire 49 to the electrically operated air valve 50 which admits air through the pipe 51 to the air brake cylinders, not shown. The current then flows through 45 wire 52 to wire 37 and thence to the battery 31, through wire 38, relay 39, and wire 40. Another portion of the current in the wire 42 flows through wire 44 to the red cab signal 53, thereby displaying a red or danger 50 signal to the engineer. This portion of the current also passes back to the battery 31, through wire 38, relay 39 and wire 40 through wire 36. Another portion of the current in wire 44 flows through wire 54 to the 55 corresponding signal 55 which may be located in one of the cars on the train at a point convenient for observation by the conductor or brakeman. The current returns through wires 37 and 36 to the battery 31, through wire 38, relay 39 and wire 40.

The yellow or cautionary circuit and its operation will now be described. When the semaphore arm E and the contact arm 9 are in the cautionary position, that is, with the contact arm 9 in contact with the contact

point 12 the yellow or cautionary circuit indicated by a dotted line will be grounded at 20 and the red or danger circuit and the green or safety circuit will both be broken. When the contact member 18 of the third rail shoe is on the part 4 of the third rail 70 the yellow or cautionary circuit is completed. In this case the current will take the following direction. It will pass from the battery or source 31 through the wires 75 32 and 33 thence through the armature of the relay 56 and then through wire 68 to the point 57. At this point the current branches and part of it passes through wire 58. It then passes through the coil *a* of a 80 double pole switch 59 then through wire 60 to the point 61 and then through wire 62 to the main switch 21 and thence to the third rail shoe. Thereafter it flows to the ground 20 as previously described. From 85 the ground 20 it passes to the ground 35 and back to the battery 31 over the same wires as have been described in connection with the red circuit, *i. e.* through wires 36, 37 and 38, through relay 39, and wire 40. 90 Beginning again at point 57 the other portion of the current passes through the wires 63 to the coil *d* of the double pole switch 28. It then passes to the point 61 and thence to the third rail through wire 62 as previously 95 described. When the current passes through the coil *d* of the double pole switch 28 it moves the armature *f* thereof to break the portion of the power circuit indicated by the wires 29 and 30 and introduces the resistance 27 into the power circuit 22 thereby reducing the speed of the train to a predetermined point. When the coil *a* of the double pole switch 59 is energized, as described, the armature *c* of the switch is attracted to the right, as shown in Fig. 1 and 100 closes a shunt circuit so that the current from the battery 31 flows through wire 64 and the yellow cab signal 65 and then through a portion of the wire 37 and the 105 wire 36 to the battery 31, through wire 38, relay 39 and wire 40. Another portion of this current flows through the wire 66 to the yellow signal 67 located in the train. The 110 return to the battery 31 is made through the wires 37 and 38, relay 39, and wire 40 as 115 previously described.

The operation of the green or safety circuit is as follows: When the semaphore arm E and the contact arm 9 are set at safety, 120 that is, with the contact arm 9 in contact with the contact point 11, the green or safety circuit indicated by a fine continuous line, will be grounded at 20 and the red or danger circuit and the yellow or cautionary circuit will both be broken. Thereafter, when the third rail shoe is in contact with the third rail, the green or safety circuit is completed. Under these circumstances the path 125 of the current is as follows: The current will 130

pass from the battery 31 through wires 32 and 33 and the armature of the relay 56, then through the wire 68 forming part of the cautionary circuit to the point 57. The 5 current branches at this point and a portion passes through the wire 63 to the coil *e* of the double pole switch 28. It then passes to the point 69 and thence through wire 70 to the main switch 21 and thence to the third 10 rail shoe and to the ground 20. From ground 20, it passes to ground 35 and back to the battery through wires 36, 37, 38, relay 39 and wire 40. When the current passes through the coil *e* of the double pole switch 28, it moves the armature *f* thereof to close the portion of the power circuit indicated by the wires 29 and 30 and cuts out the 15 resistance 27 from the power circuit 22 thereby allowing the train to run at full speed again. Beginning again at point 57 another portion 20 of the current passes through wire 58. It then passes through coil *b* of the double pole switch 59 then through wire 71 to the point 69 and thence through wire 70 to the main 25 switch 21 and thence to the third rail shoe and then to the ground 20. From ground 20, it passes to ground 35 and back to the battery through wires 36, 37, 38, relay 39, and wire 40. When the coil *b* of the double 30 pole switch 59 is energized the armature *c* is attracted to the left as shown in Fig. 1 and closes a shunt circuit so that the current from the battery 31 flows through the wire 72, green cab light 73 and then through the 35 wires 37 and 38, relay 39, and wire 40 to the battery 31, the last mentioned wires being part of the danger circuit. Another portion of this current flows through wire 74 to the corresponding green signal 75 located 40 in the train. The current returns to the battery 31 through the wire 37 as just described.

The closed circuit relay 56 which is in the 45 danger circuit is used to obtain a proper successive action of the three circuits. When the danger circuit is closed, the relay 56 breaks the safety or cautionary circuit as the case may be. When the danger circuit is again broken the relay closes the circuit 50 through the wire 68 and the circuit which was last in use whether green or yellow, is again in operation because the armature of the switch 59 was left in contact with one of the poles of the switch when the circuit was 55 broken by the closing of the red circuit.

The three cab signals are shown at 53, 65 and 73 respectively, and are connected with 60 corresponding signals 55, 67 and 75 in one or more of the cars attached to the train. This is conveniently done by means of a cable containing the various wires necessary for the circuit, said cable being connected between cars by means of plugs not shown. I also find it convenient to combine a 65 telephone system, the instruments of which are

shown at 76 and 77 respectively, the former instrument being in the cab and the latter instrument being located in one of the cars.

As danger or inconvenience might sometimes result from the failure of the system 70 to operate owing to diminution of the current supplied by the battery 31 which operates the red, yellow and green circuits I provide in the danger portion of the circuit which is common to the cautionary and 75 safety circuits and through which current from the battery 31 is always flowing to give a continuous display of signals in the cab, the open circuit relay 39 which so long as the current in the danger circuit is sufficient 80 for the requirements of the system keeps the supplementary battery circuit 78 open. The battery for the supplementary battery circuit is shown at 79. The instant the current in any of the circuits falls below the predetermined point the relay 39 closes the supplementary battery circuit 78 and rings the bell 80 or if desired stops the train by energizing the danger circuit. Whether the bell 85 is rung or the train is stopped, will depend 90 upon the position of the switch 81.

The electrically operated air valve 50 will now be described. Referring to Figs. 2 and 3, there will be seen at 82 and 83 two coils through which the current of the red circuit 95 passes. Above said coils 82 and 83 is an armature 84 pivoted at 85. Said armature 84 has a notch *b* near its end. When the red circuit is closed, as previously described, the armature 84 is drawn down and the notched end is raised sufficiently to allow an arm 86 to be pulled by a spring 87 in the direction of the two coils 82 and 83. The arm 86 is secured to an axle 88 on which is a small gear 89. Said gear 89 meshes with a rack 90 sliding in suitable guides. The end of the rack 90 engages the valve handle 91 which moves the valve member. When the two coils 82 and 83 are energized by the closing of the red circuit, the rack 90 is 100 pulled out of engagement with the valve handle 91 and spring 92 pulls the valve handle over and opens the valve, thus admitting air to the brakes. The valve cannot be reset to release the brakes until the red circuit is again closed by resetting the circuit closing relay 34. When this is done the armature 84 is 110 released. It is then pushed up into normal position by the spring 93. Then the valve may be closed and the parts restored to the position shown in Figs. 2 and 3 by pulling over the handle 91 of the valve. It will be seen from the foregoing that this cannot be done after the brakes have been set automatically until the conductor has 115 reset the circuit closing relay 34. The valve may be closed and the parts restored to the position shown in Figs. 2 and 3 by pulling over the handle 91 of the valve. It will be seen from the foregoing that this cannot be done after the brakes have been set automatically until the conductor has 120 reset the circuit closing relay 34.

In Fig. 4 is shown an apparatus embodying my invention as applied to a steam operated train. At 94 is shown a valve in the steam pipe leading to the cylinders of the 125

engine. This valve is moved by the piston rod 95 which itself is actuated by air pressure in a cylinder 96 supplied from the train pipe 97. The flow of air to the cylinder 96 is controlled by the electrically operated control valve 50 which is connected with and operated by the danger circuit. At 98 is shown another throttle valve also in the steam main which is referred to as the speed reducing throttle valve. By this valve, the speed of the train is reduced by the cautionary circuit but the brakes are not set nor is the train actually stopped. This valve is actuated by a motor 99 which is connected to both the cautionary and safety circuits. The motor 99 has on its main shaft a gear 100 meshing with a gear 101. The shaft 102 for the gear 101 carries a contact arm 103 which rests upon the circular disk 104. The said circular disk 104 and the contact arm 103 together form a rotating switch. This disk 104 is provided with two insulated spaces 105 and 106 and two conducting sections 107 and 108. The section 107 of the switch is connected to the yellow or cautionary circuit by a wire 109, while the section 108 is connected to the safety or green circuit by a wire 110. The movable contact arm 103 is connected to the motor 99 by the wire 111. The axle 112 of the motor 99 also carries a gear 113 meshing with a larger gear 114 on the shaft 115 of the speed reducing throttle valve 98.

The operation of the electrical apparatus as applied to a steam train is substantially the same as has been described in connection with Fig. 1. Assuming that the semaphore arm E is in the danger position as shown in Fig. 4, the current will flow through the battery 31, through the wires 32 and 33, through the coil of the circuit closing relay 34, to the main switch 21 and thence to the ground 20, as has been previously described. From the ground 20 it will pass to the ground 35, thence through wires 36, 37 and 38, the open circuit relay 39 and wire 40 to the battery 31. The closing of the relay 34 permits another part of the current to flow through wire 32, wire 321, through the armature of the circuit closing relay 34 to the wire 42. Part of the current operates the recording device 45 and the alarm bell 46, and then goes to the electrically operated air valve 50 and another part of the current flows through the red cab signal 53 and the auxiliary red signal 55 and returns to the ground all as previously described. This action of the current operates the air valve 50 admitting air through the pipe 51 to the air brake cylinders, and through the pipe 120 to the cylinder 96 which operates the steam valve 94.

When the semaphore arm E is in the cautionary position and the third rail shoe 65 is in contact with the third rail, the current

from the battery passes through the wires 32 and 33 forming part of the danger circuit, thence through the armature of the relay 56, then through the wire 68 to the coil *a* of the double pole switch 59, thence 70 it passes to the third rail through the wire 60 and thence to the ground 20. Thereafter it flows to the ground 35 and back to the battery 31 over the wires 36, 37, and 38, relay 39, and wire 40 as described previously. The passage of the current through the coil *a* of the double pole switch 59 pulls the armature *c* to the right and the current then passes through the yellow cab signal 65 and returns to the ground 35, 80 through wires 37 and 36. Thence it passes to ground 20 and back to the battery through wire 16, the third rail shoe, main switch 21 and wires 33 and 32. Another portion passes through 66 to the auxiliary yellow 85 signal 67 and returns to the ground as previously described. Another portion of the current continues along the wire 109 to the contact 107 of the revolving switch 104. The current passes through the contact arm 90 103, when said contact arm rests on contact 107 of the revolving switch 104, and the wire 111 to the motor 99. From the motor it passes through wire 121 to the ground 35 along wires 37 and 36. Thence it passes to ground 20 and back to the battery through wire 16 the third rail shoe, main switch 21, and wires 33 and 32.

The operation of the safety or green circuit is as follows: Assuming that the semaphore and third rail shoe are in their proper positions, the current passes from the battery 31, then through wires 32 and 33 and the armature of the relay 56, then through the wire 68 forming part of the cautionary circuit through the coil *b* of the double pole switch 59 and then through wire 71 to the main switch and back to the ground 20 as previously described. Thence it passes to the ground 35, and back to the battery 31 through the wires 36, 37, 38, relay 39, and wire 40. When the current passes through the coil *b* the armature *c* of the double pole switch 59 is moved to the left breaking the cautionary circuit and permitting the current to flow into the wire 72; a portion of this current lights the green cab signal 73, another portion lights the auxiliary signal 75 and the remainder of the current flows through wire 110 to contact 108 of the revolving switch 104. It then passes through the contact arm 103 to wire 111 and into motor 99. From motor 99 it returns by wire 121 forming part of the cautionary system as previously described to the ground 35 along wires 37 and 36.

When the safety circuit is closed, the motor 99 begins to revolve and moves the movable contact arm 103 around the disk 104 until the circuit through the motor is 130

broken by the contact arm passing off the section 112, the other section being dead. The motor then stops as its power is cut off. The movement of the motor also operates 5 the speed reducing throttle valve 98 through the gears 113 and 114, and the valve is left open at the time when the motor stops.

When the yellow or cautionary circuit is closed, the motor 99 is again started and the 10 contact member makes another half revolution, thereby partially closing the speed reducing throttle valve 98, and the circuit through the motor is broken by the contact arm passing off the other section 107. It 15 will be seen that this mechanism operates the speed reducing throttle valve entirely automatically so that the valve is open when the green circuit is closed and the valve is closed to the predetermined amount when 20 the yellow or cautionary circuit is closed, no hand operation being necessary.

From the foregoing description it will be seen that if the danger circuit is grounded anywhere the circuit will be closed and the 25 train stopping devices will be operated. If the safety or cautionary circuits are grounded or short circuited or if a wire is broken, either the trouble alarm bell 80 will ring or the train stopped according as the switch 30 81 is set. This occurs because there is no longer any current through the relay 39.

At 116 is shown a check valve which keeps the air from going to the cylinder 96 during service applications of the brakes 35 but does not interfere with it when the valve 50 acts.

While I have shown in the drawings and described herein a specific electrically operated air valve (see Figs. 2 and 3) I have 40 not claimed the same herein, as I believe it to be an independent invention.

What I claim is:

1. In a train arresting mechanism, the combination of a semaphore capable of being set in three positions to indicate danger, caution and safety, a contact device operated thereby and provided with three contacts corresponding to the semaphore positions, a contact rail having a longitudinal 45 50 conducting surface secured to each side

thereof but electrically separated therefrom the contact rail being connected to the semaphore contact corresponding to the danger position and the two side conducting surfaces being connected to the other two semaphore contacts, a shoe carried by the train and provided with three brushes one resting on the top of the rail and the other two on said conducting surfaces, and three electric circuits on the train corresponding to 55 the three semaphore positions, the danger circuit being connected to the brush on the top of the rail and the other two circuits being connected to the other two brushes.

2. In a train arresting system, the combination of a multiple position semaphore, a contact member operated by said semaphore, electric train circuits controlled by said contact member, a speed reducing control device acting to reduce the supply of motive power, a separate device operating to cut off entirely the motive power, said two devices being operated by two train circuits.

3. In a train arresting system, the combination of a multiple position semaphore, a contact member operated thereby, electric train circuits controlled by said contact member, a speed reducing device acting to reduce the supply of motive power, a separate device operating to cut off entirely the supply of motive power, and an air brake actuating device, said speed reducing device being in one train circuit and said separate device and said air brake actuating device 80 being both in another train circuit.

4. In a train arresting device, the combination of two train circuits, a speed reducing device, an electric motor moving said speed reducing device, said motor being 90 connected to both said circuits, and a revolving switch moved by the said motor and operating to alternately make and break the said two circuits.

In testimony whereof I affix my signature, in presence of two witnesses.

GEORGE A. WILSON, JR.
